UNITED STATES PATENT OFFICE.

DWIGHT J. LAWTON AND HOMER I. REYNOLDS, OF GRANTS PASS, OREGON.

SMOKE-PURIFIER AND GAS-COLLECTOR.

No. 798,287.

Specification of Letters Patent.

Patented Aug. 29, 1905.

Application filed December 30, 1904. Serial No. 239,013.

To all whom it may concern:

Be it known that we, DWIGHT J. LAWTON and HOMER I. REYNOLDS, citizens of the United States, residing at Grants Pass, in the county 5 of Josephine and State of Oregon, have invented a new and useful Smoke-Purifier and Gas-Collector, of which the following is a specification.

This invention relates to improvements in 10 apparatus for arresting and purifying smoke, gases, and other products from the combustion in furnaces of various kinds, coke-ovens, smelters, and similar apparatus, and all the various operations wherein fuel is employed 15 and wherein smoke, gases, fumes, and similar products result from the combustion, and has for its object to produce a simply-constructed apparatus into which the smoke, gases, and other products of the combustion are caused 20 to pass and wherein the heavier particles are precipitated and the heavier gases and fumes condensed and the residuum retained for future restoration and reduction to save the valuable portions, leaving the lighter and 25 more volatile gases only to escape.

With these and other objects in view, which will appear as the nature of the invention is better understood, the same consists in certain novel features of construction, as hereinafter fully described and claimed.

In the accompanying drawings, forming a part of this specification, and in which corresponding parts are denoted by like designating characters, is illustrated the preferred 35 form of embodiment of the invention capable of carrying the same into practical operation, it being understood that the invention is not necessarily limited thereto, as various changes in the shape, proportions, and general assembly 40 of the parts may be resorted to without departing from the principle of the invention or sacrificing any of its advantages.

In the drawings thus employed, Figure 1 represents a side elevation, partially in section, of the improved apparatus applied. 45 Fig. 2 is an enlarged transverse section of the receiving-drum on the line 2 2 of Fig. 1.

The improved apparatus comprises a drum 10, having conical ends 11 12 and with an 50 intake-pipe 13 at one end to supply water under pressure and with a discharge-pipe 14 at the other end. The intake-pipe 13 is provided with a controlling-valve 35 to provide means for regulating the flow of the water to 55 the drum. Disposed in the drum 10, preferably at the juncture of the conical portion 11

and the body of the drum, is a perforated plate 15, forming a grate or diaphragm transversely of the drum and through which the water entering by the pipe 13 pours in the 60 form of jets or sprays. Leading into the side of the drum 10 is a relatively large conductor-pipe 16, the pipe entering the drum at a downward incline and with the outer end connected into the smoke-stack 17, rising from 65 the smelter, furnace, or other structure from which the smoke, gases, and the like rise and which it is desired to purify and condense.

For the purpose of illustration a conventional form of the structure from which the 70 products of the combustion arise is indicated at 18; but it will be understood that we do not desire to be limited in any manner in the application of the apparatus to any particular structure, as the source of the smoke, gases, 75 fumes, and the like is no part of the invention.

The stack 17 is provided with a damper 19 to provide for a direct draft from the structure 18 when first starting the fires therein or 80 at other times when required. Disposed in the pipe 16 are blower-nozzles 20, preferably two or more and pointing downwardly into the inclined portion of the pipe and connected to a pipe 21, through which steam or compressed air may be forced to produce strong 85 artificial or induced air currents through the pipe to cause a strong draft from the structure 18 into the drum 10. The pipe 14 leads into one end of a receiver or tank 22, and this 90 tank is connected by a branch 23 to another similar tank 24, from which an escape-pipe 25 leads, as shown. The tanks are connected by a branch 26, preferably supplied with a controlling-valve 27, and the last tank 24 is 95 also supplied with an overflow-pipe 28, the valve 27 providing means whereby the water may be caused to flow through all the tanks uniformly. The tanks are provided, respectively, with discharge-pipes having 100 controlling-valves 29 30 and also with "manholes" 31 32 to afford means of access to the tanks for cleaning the same when required. The tank 22 is also provided with a pressure-gage 33 and water-gage 34 of the usual construction. Two of the tanks are shown connected, as described; but it will be understood that any required number may be employed, according to the condition or quality 105 of the products of the combustion conducted to the drum 10.

In the operation of this device water is ad-

mitted to the drum 10 through the valved supply-pipe 13, the said water-supply being under pressure, as stated. The perforated dia-phragm 15 within the drum is located at the 5 widest part of this drum and quite a distance below the inlet, thus causing the entering wa-
ter to fall heavily upon the perforated dia-
phragm and to pass through the latter in nu-
merous jets. The escape-pipe 14 at the bot-
tom of the drum is of sufficient diameter to
enable the water to escape freely, and said
water, thus rushing through the drum, will
create a downward suction in the downward-
inclined pipe 16, which forms a conductor for
10 the products of combustion arising through
the stack 18. Thus suction may be assisted
when desired, and especially at the begin-
ning of the operation, by introducing com-
pressed air or steam into the conductor 16
15 through the nozzles of the pipe 21. The
products of combustion will be carried rap-
idly through the drum 10 by the downwardly-
rushing jets of water and will be conducted
with the water into the first tank 22, the
20 effect of the water being to suddenly con-
dense the heated gases and smoke and pre-
cipitate the particles of unconsumed carbon
and other heavier matter, leaving the lighter
gases only to pass through the by-pass 23 to
25 the second tank, where they come in contact
with the water therein and are still further
condensed and through as many tanks as
may be required, leaving only the very light
and volatile gases to escape at the final vent-
30 pipe 25. When a sufficient quantity of the
sediment has accumulated in the tanks, it is
removed through the discharge members 29
35 30, and, if necessary, the manholes 31 32
may be removed to permit the operatives to
40 enter the tanks and clear the same from the
accumulations.

The material settling in the tanks often con-
tains valuable matter, and after its removal
it can be suitably treated for saving the de-
45 sirable portions.

The device is simple in construction, effi-
cient in action, and capable of a wide range of

application, as will be obvious, and can be
constructed of any required size to adapt it
to all the various sizes of furnaces and like 50
structures manufactured.

The apparatus is especially valuable for pre-
venting the escape of injurious and unpleas-
ant fumes and gases from smelters and simi-
lar structures and from chemical-manufactur- 55
ing plants and the like.

The apparatus may be associated with other
forms of apparatus, such as settling-tanks
and the like, either opened or closed; but this
would not affect the invention or modify or 60
otherwise interfere with its action.

Having thus described the invention, what
is claimed is—

1. In a device of the class described, a ver-
tically-disposed drum having conical ends, a 65
downwardly-inclined smoke-conductor con-
nected at its lower end with the cylindrical
body of said drum and at its upper end with
a smoke-stack, a perforated diaphragm mount-
ed in the drum directly below the upper con-
ical end, and means for supplying water-un-
der pressure to the upper extremity of said
upper conical end of the drum.

2. In a device of the class described, the com-
bination of a drum having contracted upper 75
and lower ends, an inclined smoke-conductor
connected at its lower end with the body of
the drum and at its upper end with a smoke-
stack, means for conducting water under pres-
sure through said drum to thereby set up a
suction in the smoke-conductor, and settling-
tanks one of which is connected with the lower
80 end of the drum; said settling-tanks being
connected with each other by a valved pipe
and by an arched by-pass.

In testimony that we claim the foregoing as
our own we have hereto affixed our signatures
in the presence of two witnesses.
